FLUID LEVEL INDICATOR

Archibald H. Davis, Jr., Cleveland, Ohio, assignor
to American Machine and Metals, Inc., East
Moline, Ill., a corporation of Delaware

Application December 20, 1943, Serial No. 515,011

2 Claims. (Cl. 177—311)

1

This invention consists of means adapted to respond to the arrival of a frothy fluid, such as foam, suds or the like, at a preset level in a receptacle.

One application for the invention is found in making a mixture of two or more ingredients, at least one of which is in liquid form and which will, when agitated, form a froth or suds and where the proportion of the ingredients is to be so adjusted that a given head of froth or suds will be formed. The invention is adapted to automatically operate an indicating device or to automatically shut off the further supply of one ingredient when the proper proportion is reached. Variable factors that cannot readily be evaluated in advance may require using a quantity of the suds-forming ingredient that is not constant for each charge even though a given head of suds is to be attained and the amount of the other ingredient is always the same.

Such a problem is encountered in the operation of an automatically controlled machine for washing fabrics. To secure satisfactory cleansing action such an amount of detergent must be added to the water as will build up a suds blanket of a given depth in any particular machine. However, not all the detergents added are available for forming suds. Many complex reactions take place between the soil contained in the fabrics that are being cleansed, the minerals or other materials in the water generally referred to as "hardness" of the water, and the detergents. As a result of these reactions a part of the detergent is used to form compounds with the soil and the hardness creating substances in the water. The quantity of detergents used in this manner varies in proportion to the amount of soil and the hardness of the water. Therefore, the total amount of detergent to be added to the bath to achieve the desired washing results will vary in proportion to the larger or smaller losses of detergent in the reactions just mentioned. Usually several successive suds treatments are applied to the fabrics and the amount of detergent used for other than suds-forming purposes varies in successive treatments.

It is an object of this invention to provide a method and apparatus which will permit detection from without a container when the frothy liquid reaches a preset level therein.

It is a further object of this invention to use the difference in frictional resistance to fluid flow offered by the air and a frothy fluid to operate an indicating or operation-controlling device when the frothy fluid reaches a preset level.

2

A further object of the invention is to provide a device permitting a suds-forming ingredient to be added without measurement to a bath and yet secure a predetermined proportion. The device comprises a pressure responsive cell which shuts off the further flow of the suds-forming ingredient when there is a sudden change in the pressure acting on the cell as a result of the suds having risen to a desired height.

- 10 A further object is to provide a device which responds when the top of the suds blanket extends a fixed distance above the previously fixed level of water, the response resulting from a change in suction exerted by a vacuum-creating device that is operated by a means other than the fluid whose level is to be controlled.
- 15 A further object of the invention is to provide pressure responsive means which will detect when a fluid, which is composed at least in part of a liquid, reaches a preset level in a container wherein the operation of the pressure responsive means does not depend upon the particular specific gravity of the fluid whose level is being detected.
- 20 Another object of the invention is to provide means adapted to successively detect the arrival of one or more fluids in a container at successive levels.

Other objects of the invention will become apparent as the description proceeds, reference being made to the accompanying drawings in which:

Fig. 1 is an end elevation, partly in section, of a receptacle equipped with the invention and

Fig. 2 is an elevation, partly in section, of a control box shown in Fig. 1 together with the mechanism controlled by circuits coming from the box.

- 10 denotes a stationary receptacle adapted to be filled to a level *a* with a liquid, such as water. 40 A cylindrical container *11* for the material to be treated is rotatably supported on a shaft *12* supported by receptacle *10*. This shaft may be driven by any suitable mechanism, not shown, to agitate the contents of the cylinder in the liquid contained in the receptacle.

A pipe *13*, provided with a contraction *15*, connects a point in the receptacle at a level *b* which is above level *a*, to a vacuum-creating device *14*, such as a centrifugal exhaust pump. A pipe *16* branches off from pipe *13* at a point intermediate the receptacle and the contraction *15* to a control box *17* shown in detail in Fig. 2. Pipe *16* connects to a casting *19* that contains a suction chamber *18* and supports the rest of the mechanism. The suction chamber *18* is closed

by a flexible diaphragm 21 whose edges are held firmly between a flange 20 of the casting 19 and a ring 22. A spring 23 tends to push the diaphragm outwardly. Ring 22 carries lugs 26 that pivotally support a lever generally indicated at 24. An arm 27 of the lever 24 has a projection 28 on one side and a light spring 29 is attached to its free end. This spring is anchored to a finger 30 carried by flange 20 of casting 19. Spring 29 tends to keep the projection 28 of the arm 27 in contact with the diaphragm 21. A projection 32 on another arm 31 of lever 24 is adapted to limit the outward movement of the diaphragm pressing against projection 28 when projection 32 bears against a stop 33 on ring 22. A third arm 34 of lever 24 is adapted to close an electric circuit through contacts 35, 36 when the diaphragm 21 forces the lever 24 to rotate about its axis 25, bringing the stops 32 and 33 in contact, and to open the circuit when the suction in chamber 18, together with the pull of spring 29, overcomes spring 23.

Contacts 35, 36 form part of an electric circuit of any type that is adapted to give a signal or to control an operation. Fig. 2 shows such a circuit 41, 42 coming from a controller not shown. When contacts 35 and 36 are in contact and the circuit 41, 42 is energized by the controller, that is not shown, current will flow from 41 thru solenoid 37, lead 40, contact 36 contact 35 to lead 42. This will open the valve 38 controlled by the solenoid and permit liquid to flow thru pipe line 39 into the washer as long as contacts 35 and 36 engage each other.

The invention will now be further described in its application to a washing machine in which fabrics are cleansed by agitating them in a bath of water to which suds-forming detergent is added. Assuming that 10 and 11 are respectively, the outer shell and the rotatable cylinder of such a washing machine, that the pipe line 39 is the line through which suds-forming detergent is supplied by the washer, that the shell 10 is filled with water up to the level *a* in Fig. 1, and that the rotatable cylinder 11 has been loaded with a certain weight of soiled fabrics, the operation of the device as has been described so far is as follows: while the cylinder 11 and its contents are agitated, detergent is slowly added through the pipe line 39 to the water in the receptacle 10, the circuit containing the solenoid 37 having been established by some agency such as a controller, in a manner well known in the art. As the detergent mixes with the water, part of the detergent combines with the soil of the garments and with solids contained in the water. It will depend upon the nature and the quantity of the soil present in the fabrics and of the minerals and other solid substances contained in the water, whether a smaller or a larger total amount of detergent will be necessary for the given volume of water to prepare a mixture in which there is neither too much nor too little detergent present. Where more of the detergent is combining with the soil and the solids in the water, a larger total quantity of detergent will have to be supplied in order to leave sufficient free detergent for the process of forming suds. On account of the variables just mentioned it is not possible to determine the amount of detergent required to achieve the optimum washing effect by way of adding such detergent in a constant proportion to the water. It has been found that a reliable indication as to when the addition of suds-forming detergent to the bath ought to

be terminated resides in the arrival of the suds at a predetermined level situated a certain distance above the fixed water level. This discovery is described in detail in the application Serial No. 438,984, now Patent No. 2,430,668, of John W. Chamberlin, filed April 15, 1942, and assigned to the assignee of the present application. The level *b* of Fig. 1 at which the conduit 13 opens into the receptacle 10 is the predetermined suds level just mentioned.

As long as the suds are forming on top of the water level *a* but have not reached the level *b*, the pump 14 is drawing air through the conduit 13. There will be a uniform drop in pressure along the conduit 13 due to friction, and a large drop will take place at the contraction 15 beyond the point where the suction chamber 18 is connected to the conduit 13. While under these conditions a slight suction is exerted through the pipes 13 and 18 upon the suction chamber 18, this suction is quite insufficient to overcome the force of the spring 23. The spring 23, therefore, keeps the diaphragm 21 pressed against the projection 28 of the lever 24, the latter maintaining by means of its arm 34 the contacts 35 and 36 in their closed position. Thus the circuit containing the solenoid 37 remains energized, keeping open the valve 38 in the pipe line 39 so that detergent is continuing to be supplied through the pipe line 39 into the receptacle 10.

When the suds blanket forming on top of the water rises to the level *b*, the pump 14 which thus far has been drawing air into the conduit 13 draws a new fluid, suds, into the mouth of pipe 13. I have found that such suds offer a frictional resistance so much greater than the friction of the air to the passage through pipe 13 that a sharp increase in the suction in conduit 13 and particularly in chamber 18 will take place. This suddenly increased suction is strong enough to draw the diaphragm 21 inwardly against the action of the spring 23 permitting the spring 29 to turn lever 24 in a clockwise direction to release the contact 35 thereby interrupting the circuit of the solenoid 37. The detergent valve 38, no longer held in open position by the solenoid 37, closes the flow through the pipe line 39, thereby preventing the further supply of detergent to the bath in the receptacle 10.

The agitation that continues after the supply of detergent is shut off draws in air that tends to increase the height of the suds blanket. At the same time, the soil still in the fabrics combines with some of the detergent in the suds, thus tending to lower the suds level. Where several successive treatments are applied, in the first suds the latter tendency has the upper hand, so the suds level falls below level *b*. As the fabrics become cleaner in subsequent treatments the tendency of the suds to fall because the detergent combines with the soil decreases, and in later suds there is a tendency for the suds level to rise above *b*. Experience has shown that if agitation is continued after the detergent supply is shut off for a fixed time the suds level rises to a certain level and the fabrics may be considered clean, except that the detergent must still be rinsed out. This upper suds level is indicated in Fig. 1 at *c*. For detecting the arrival of the suds at this level *c* a control device 43 similar to the control box 17 just described in connection with the detection of the suds blanket at the lower suds level *b* is used. The inner construction of the box is the same as that shown for the box 17 in Fig. 2 and the suction chamber in the box 43

5

is connected by means of a branch pipe 44 to a conduit 45 entering the receptacle 10 at the level *a*. Beyond the pipe 44 the conduit 45 could be connected to the same pump 14 as is the conduit 13, but I have illustrated the conduit 45 as being connected to a separate vacuum creating device in the form of an ejector 46 having a nozzle 47. The ejector is operated by a stream of water passing through a pipe 48 controlled by a valve 49. Since the quantity of water passing through the pipe 48 is negligibly small compared with the body of water contained in the receptacle 10, the water coming through the pipe 48 can be discharged into the receptacle 10, rather than into a sewer, without affecting the washing operation one way or the other. The ejector 46 draws air into and through the conduit 45 as long as the suds have not reached the level *a*. When they do reach this level there is a sudden increase in suction acting upon the diaphragm in the control box 52 and the contacts in that control box are opened. These contacts form a part of a control circuit of the general type shown in Fig. 2. A solenoid similar to 37 may in this case operate an indicator that will indicate to the operator that the washing operation is complete and that the next stage, which might be rinsing, can commence. Or the solenoid 37 might cause the automatic control mechanism of the washing machine to shift from washing to rinsing upon completion of the suds treatment in progress, after the dump valve has finished discharging the spent bath.

The vacuum-creating device, whether 14 or 46, is operated by means other than the fluid whose level is to be detected. In the case of the ejector 46, for instance, a separate water supply line 48 operating the ejector is provided in addition to the detergent supply pipe 39. This makes the operation of the devices in the control boxes independent of the characteristics of the particular fluid upon whose arrival at a certain level some indication or controlling operation has to take place. It also permits use of a common vacuum-creating device in connection with the control of the levels of a plurality of fluids, even though these fluids may be of different kinds, such as, e. g., suds and water. An arrangement of this kind is shown in Fig. 1 where the conduit 13 leading to the lower suds level *b* as well as a conduit 50 communicating with the receptacle 10 at the level *a* which is the level to which the receptacle is to be filled with water is connected to the exhaust pump 14. A control box 52 of a construction similar to that shown in Fig. 2 for the control box 17 is connected by means of a pipe 51 to the conduit 50 intermediate the two ends of the latter, and a contraction 53 is provided in the conduit 50 at a point between the pump 14 and the branch pipe 51. The electric contacts in the control box 52 may operate a solenoid 54 controlling the water inlet valve 55 of the washing machine.

The device 52 operates in substantially the same manner as the device 17. As long as the water which may be supplied to the receptacle 10 by a pipe 56 has not reached the predetermined water level *a*, the pump 14 draws air through the conduit 50 and the suction active through the branch pipe 51 upon the diaphragm in the box 52 is too small to permit an inward flexure of that diaphragm. When the water reaches the level *a* at which the conduit 50 is connected to the receptacle 10, water, instead of air, enters the conduit 50. The water offers a very much higher resistance to the action of the pump 14 than did

6

the air and a suction of greater strength develops in the suction chamber of the device 52. As a result of this suddenly increased suction the diaphragm of the device 52 is drawn inwardly against the force of its coordinated spring 23, the contacts 35, 36 are broken in the manner described in connection with the control box 17, the solenoid 54 is deenergized and the valve 55 in the water pipe 56 closes.

10 It is to be noted that as the water rises in the vertical pipe 50 there will be a further increase of suction because of the head of water in the pipe 50. This is, however, inconsequential since the device in the control box 52 will operate to open 15 the contacts 35, 36 in that box as soon as the first drops of water are drawn into the pipe. This takes place long before the pipe actually becomes filled with liquid.

As has been mentioned before, the conduit 45 20 could also be connected with the pump 14 from which, according to Fig. 1, the conduits 13 and 50 are branched off, so that the arrival of the water at the level *a* as well as the successive rise of the suds first to the level *b* and then to the level *c* 25 would all be detected and made use of under the action of suction brought about in all three cases by one and the same vacuum-creating device 14.

Where several level-detecting devices are connected to the same vacuum creating device, it will 30 be useful in certain cases to provide some or all of the conduits leading from the receptacle 10 to the common pump or the like with valves for cutting off the particular conduit when the detecting device to which that conduit is coordinated operates its diaphragm. I have indicated such a valve at 57 behind the contraction 53 in the conduit 50. This valve may be controlled by a solenoid 58 arranged in parallel to the solenoid 54 so that the water supply valve 55 and the valve 40 57 in the conduit 50 will open and close in unison. In this manner little or no liquid is drawn over into the pump because the flow is cut off as soon as the level has been detected.

It will be apparent from the foregoing description 45 that the application of my invention is not limited by such considerations as whether or not the frothy fluid whose level is to be detected differs much from air in specific gravity. The operation of a detecting device built according to 50 the invention repends upon the property of such fluid to offer, when sucked into a tube or the like, a larger flow resistance than does air, and if this property is present in a fluid, it does not matter if its specific gravity is different from the specific 55 gravity of air to an extent only which cannot be detected readily as is the case, for instance, with the suds referred to repeatedly in this specification.

While I have described my invention in its application 60 to a washer, I desire it to be understood that the invention is not restricted to such application. It is applicable wherever a process involves the formation of a frothy fluid, e. g. foam or suds, by mechanical or chemical action, and the arrival of this frothy fluid at one or more prescribed levels has some bearing upon the progress or the termination of the process. It is further to be understood that while I have shown in 65 the drawing a certain embodiment of the invention, this embodiment has been given by way of example only and that various changes, rearrangements and modifications may be made without departing from the spirit of the invention or 70 the scope of the appended claims.

What I claim is:

1. Apparatus including an aspirator drawing fluid continuously through a tube connected to the side of the tank which responds to the arrival of the surface of liquid being poured into the tank to the level of the entrance of the tube into the tank by indicating the increased suction required to draw liquid fluid rather than gaseous fluid through the tube comprising, in combination, a tank, a tube entering the tank at a given height above its bottom, a contraction in the tube, an aspirator beyond the contraction continuously drawing fluid from the tank through the conduit and the contraction, means responding to the pressure differential between the entrance of the tube into the tank and a given point in the tube between the tank and the contraction, means preventing the pressure-responsive means for responding to pressures up to the suction pressure developed by the aspirator when drawing a gaseous fluid through the tube.

2. Apparatus including an aspirator drawing fluid continuously through a tube connected to the side of the tank which responds to the arrival of a layer of foam rising in a tank to the level of the entrance of the tube into the tank by indicating the increased suction required to draw a foamy mixture of liquid and gas rather than gas alone through the tube comprising, in combination, a tank, a tube entering the tank at a given

height above its bottom, a contraction in the tube, an aspirator beyond the contraction continuously drawing fluid from the tank through the conduit and the contraction, means responding to the pressure differential between the entrance of the tube into the tank and a given point in the tube between the tank and the contraction, means preventing the pressure-responsive means from responding to pressures up to the suction pressure developed by the aspirator when drawing a gaseous fluid without foam through the tube.
